UNITED STATES PATENT OFFICE

JOHAN M. ANDERSEN, OF BROOKLINE, MASSACHUSETTS, ASSIGNOR TO ALBERT & J. M. ANDERSON MANUFACTURING COMPANY, OF BOSTON, MASSACHUSETTS, A CORPORATION OF MASSACHUSETTS

ELECTRIC SWITCH

Application filed November 7, 1923. Serial No. 673,294.

This invention relates to a circuit controlling apparatus, which is especially adapted among other uses to be employed in high tension alternating current circuits. The invention is capable of embodiment in circuit controlling apparatus for general use, but is herein shown as embodied in an apparatus designed to be located on an elevated support, such as the cross arm of a pole carrying the high tension wires, and is further designed to be embodied in an apparatus provided with an oil containing well or receptacle, within which the circuit is opened in oil. The invention has for one of its objects to provide apparatus of the character described, in which the movable member of the switch may be operated from outside of the apparatus, and in which the actuating device is capable of being moved without affecting the condition of the switch, whereby the latter is safeguarded against accidental operation, as will be described. Another feature of the invention consists in providing for automatically locking the oil well to its supporting member, whereby the operator on an elevated support such as a pole can position the oil well with one hand, as will be described. The invention further has for its object to provide a simple, efficient, reliable and durable construction of switch mechanism, as will be described.

These and other features of this invention will be pointed out in the claims at the end of this specification.

Figure 1 is a side elevation of a circuit controlling apparatus embodying this invention. Figure 2 a longitudinal section of the apparatus shown in Figure 1, the switch being shown in its closed position.

Figure 3 a like section with the switch open. Figure 4 a cross section on line 4—4, Figure 2, and

Figure 5 a plan view of the stationary supporting frame or member for the switch mechanism, with the top plate or cover therefor removed.

In the present instance, a preferred embodiment of the invention is shown, which is especially adapted for use on an elevated support such as a pole, not shown, which carries the line wires.

In the embodiment herein shown, a movable circuit controlling member 10 (see Figure 2) cooperates with stationary terminals or contact members 12, 13 in a manner well understood.

These cooperating parts are carried by a stationary supporting member or frame, herein shown as a box like structure or casting ⁵⁵ a provided with side walls 14, end walls 15, bottom wall 16, and removable top wall or cover 17.

The casing *a* forms a chamber 18 within which the mechanism for operating the movable switch member 10 is located, and supports a removable well or receptacle 19 which is designed to contain sufficient oil ⁶⁰ or other liquid to cover the movable and stationary contact members 10, 12, 13.

The stationary contact members 12, 13 are secured to the under side of a slab or plate ⁶⁵ 20 of insulating material, which is suspended by rods 21 from lugs 22 attached to the side walls 14 of the casing *a*.

The movable contact member 10 is connected by bars or strips 23 of insulating material with a movable metal member, preferably made as a crosshead *b* having a top plate 25, depending end flanges 26, and an intermediate web 27 connecting said end flanges. The web 27 has pivotally connected to it at 28, the upper end of a connecting rod ⁷⁰ 29, which has its lower end pivotally connected at 30 to a crank 31 on a rockshaft 32, which is supported in a bearing hub 33 (see Figure 4) which is extended into the chamber 18 from a side wall 14 thereof. The ⁷⁵ 30

rockshaft 32 is extended outside of the chamber 18 and has fast on it a crank or arm 35, with which cooperates a lug 36 on a handle 37 loosely mounted on the rockshaft 32 to turn thereon without effecting movement of the rockshaft until the lug 36 is engaged with the crank or arm 35. Normally the handle 37 hangs in the vertical position shown in Figure 1, and to open the switch is moved 10 in the direction indicated by the arrow 38 in Figure 1, and to close the switch is moved in the opposite direction indicated by the arrow 39. The rockshaft 32 and the pivot pin 28 are arranged in a vertical plane, and 15 the connecting rod 29 and crank 31 are constructed and arranged to form a toggle, whose center pivot 30 is carried beyond the center or vertical plane when the switch is closed, as represented in Figure 2. The connecting rod 29 is provided with a lug 40 (see 20 Figure 2) which engages an end flange 26 when the switch is closed, the said end flange acting as a stop to arrest movement of the rockshaft 32 at or about the time the switch is closed.

The switch is held in its closed position by the toggle until the rockshaft 32 is turned in the opposite direction by the operator, sufficiently far to carry the center pin 30 of the 30 toggle beyond the center in the opposite direction, whereupon the opening movement of the switch is completed with a quick throw of the movable member 10, by one or more springs 42, herein shown as two in number 35 and located in sockets 43 in the end flanges 26 of the cross head b.

The springs 42 act on plungers 44, which reciprocate in the sockets 43 and are provided with rods 45 extended through the bottom 40 walls of said sockets and provided at their lower ends with nuts 46, which are designed to engage the bottom surfaces of the end flanges 26 in the opening movement of the movable member 10 of the switch by the 45 springs 42 as will be described. The plungers 44 project beyond the cross head b and are designed to engage the cover 17 in the closed position of the switch.

By reference to Figure 2, it will be seen, 50 that when the switch is closed, the springs 42 are compressed by the plungers 44 bearing against the stationary cover 17 and that the lower ends of the rods 45 and the nuts 46 thereon are removed from the bottom surfaces of the end flanges 26 of the cross head b, so that, as soon as the centerpin 30 of the toggle passes beyond the center plane of the toggle, the springs expand downwardly and, acting on the cross head, move the movable 55 switch member 10 away from the stationary contacts or members 12 and 13 with a quick throw so as to quickly break or draw the arc in the oil contained in the well 19.

The springs 42 act to turn the rockshaft 32 60 in the direction indicated by arrow 50 until

the cross head b has been lowered away from the cover a sufficient distance to remove the action of the springs from the cross head and allow them to act on the plungers 44, which are further projected out of their sockets on the further opening movement of the movable 70 switch member 10 by gravity.

The switch member 10 is fully opened when the rockshaft 32 has been turned substantially a half revolution from the position shown in Figure 2 into that shown in Figure 3. When the switch member 10 is in its open position shown in Figure 3, the plungers 44 are projected out of their sockets the maximum distance and are removed from 75 engagement with the cover. On the closing movement of the switch, the rockshaft 32 is turned in the direction indicated by the arrow 52 from the position shown in Figure 3 into that shown in Figure 2, and in this movement 80 the crosshead b is raised and the plungers 44 are engaged with the cover 17, and on further upward movement of the crosshead, the springs 42 are compressed by the latter between the bottom walls of the sockets 43 and 85 the now stationary plungers.

The crosshead b and the bars or plates 23 of insulating material constitute a support for the movable switch member 10, and provision is made for guiding said support in its 90 movement so that the switch member 10 may be maintained in proper alignment with the stationary contact members 12 and 13.

To this end, the insulating members or bars 23 of the support for the movable switch member 10 engage rollers 54 of insulating material, which are mounted to turn freely on pins 55 carried by metal uprights or frames 56 erected upon and secured to the insulating slab or plate 20.

The uprights 56 are located on opposite sides of the crosshead b and the antifriction rollers 54 extend transversely of the insulating bars 23 and are provided with end flanges 57, which overlap the sides of the insulating bars 23 as shown in Figure 5, thereby confining the support for the movable member 10 within definite limits. The stationary contact members or terminals are electrically connected within the chamber 18 by conducting strips or members 60, with line terminals 61 also located within the chamber 18 and supported by insulators 62 extended through suitable openings in the bottom wall 16 of, 105 said chamber.

Provision is made for supporting the oil well 19 from the casing a by means which automatically engage the oil well, which allows the latter to be held in one hand of the operator and moved upwardly into position, and on this upward movement to engage the supporting devices and move them backward out of the path of the well and permit the latter to be raised into its operative position, whereupon the supporting devices are 110 115 120 125 130

automatically brought into the path of movement of the well to engage and support the same independently of the operator, who can then remove his hand from the well.

5 In the present instance one construction of supporting device is shown but it is not desired to limit this feature of the invention to the particular construction shown. The supporting devices herein shown consist of 10 angle-shaped levers or swing arms 64, pivoted at their upper ends to the bottom wall 16 of the casing *a* at opposite ends of an opening 65 in said bottom wall and adjacent thereto. The swing arms or levers 64 are 15 provided with fingers 66, which project toward the opening 65 and into the path of lugs or ears 67 attached to the opposite sides of the oil well 19 and provided with a substantially flat under surface 68 and with an inclined or cam-shaped surface 69. The cam-shaped surfaces 69 engage the fingers 66 of the swing arms as the oil well is moved upwardly into position, and turn the swing arms backward until the lugs or ears 25 have been carried past the said fingers, whereupon the latter are moved toward the oil well by gravity alone as herein shown or by gravity assisted by a spring, not shown, in a manner well understood, and the fingers 66 are brought under the lugs or ears 68 into 30 position to support the oil well. The operator can then remove his hand from the oil well, and the latter will be supported by the swing arms.

35 The swing arms 64 may and preferably will be provided with set screws 70 for engaging the lugs or ears 67 and setting up the oil well against the bottom wall of the casing *a* in fixed relation thereto, so as to effect a tight joint therewith by means of a gasket 71.

40 Provision is made for suspending the apparatus from an elevated support such as the cross arm of a pole carrying the line wires. To this end the cover or top plate 17 is provided with angle ribs 72 (see Figure 4), which cooperate to form an inverted T-shaped slot 73 for the reception of one or more bolts 74 attached to a metal plate 75 which is designed to be bolted to the under 45 side of the cross arm, not shown. The head of the bolt 74 is received in the enlarged portion of the slot 73 and engages the under surface of the arms 76 of the ribs 72. The cover 17 may be engaged with the bolts 74 by entering the latter from either end of the 50 slot 73. The oil well 19 may be provided with a supply pipe 80 normally closed by a removable plug 81 and through which the oil may be supplied after the apparatus has been 55 installed in position, and it may also be provided with a drainage outlet normally closed by a plug 82.

60 The side wall of the casing *a* through which the rockshaft 32 is extended may and preferably will have thereon the words "Open"

and "Closed" (see Figure 1) and the crank or arm 35 is secured on the rockshaft so as to cooperate with these words respectively when the switch is open and closed.

65 The crank or arm 35 serves as an indicator and enables the operator to see at a glance what position the switch is in.

In Figure 1, the crank or arm 35 points to the word "Closed" and if the operator desires to open the switch, he turns the handle in the direction of the arrow 38 until the lug 36 is engaged with the under side thereof, after which the handle is further moved in the same direction until the centerpin 30 of the toggle has been carried beyond the center, whereupon the springs 42 effect a quick opening of the switch as above described. The operator then releases the handle, which turns freely on the rockshaft back into its normal vertical position. The crank or arm 35 now points to the word "Open", and to close the switch, the operator turns the handle in the direction indicated by the arrow 39 until the lug 36 is engaged with the under side of the crank or arm 35, and then continues to turn the handle further in the same direction, until further movement is prevented by the lug 40 on the toggle lever 29 engaging the end flange 26 with which it cooperates as shown in Figure 2.

70 It will be observed that the closing of the switch is effected by the operator, whereas the opening of the switch is started by the operator and continued by the springs 42 independently of the operator, so that the operator after starting the opening movement is powerless to stop it. In the closed position of the switch, the toggle is held off the center with the stop lug 40 against the end flange 26 by the springs 42, which are made of such strength as to prevent the switch being accidentally opened by vibrations in the street or on the top of the pole. It will also be observed, that the handle 37 may be accidentally turned by a lineman or other operator without operating the switch, as the handle is free to swing on the rock-shaft and is normally disconnected from the switch.

75 The cover 17 may and preferably will be provided with strengthening ribs 90.

80 While the switch herein shown is especially useful for employment on poles or other elevated structures, it is not desired to limit the invention in this respect.

85 By reference to Figs. 4 and 5, it will be observed that the bars, strips or pieces 23 of insulating material are of substantially the same width as the fixed contact members or terminals 12, 13, and are movable with the movable contact member 10, so that they support the latter in its movement away from the fixed contact members and constitute a barrier between the latter for the passage of the arc from one fixed contact member to the other.

It will be observed that the bars, strips or pieces 23 are of such length that the insulating barrier is maintained between the fixed contacts 12, 13, while the movable contact member 10 is being moved from its closed to its open position.

A water-tight joint is effected between the cover 17 and the casing *a* by a gasket 73 and a like joint is effected between the oil well 10 and the casing *a* by the gasket 71, thereby effectively preventing the entrance of water into the apparatus except at the rock-shaft 32, and to prevent or at least reduce to a minimum the liability of water passing into the casing *a* along the rock-shaft, the latter is provided with preferably a plurality of annular grooves 94, herein shown as three in number, which are located near the outer end of the bearing 33 for the rock-shaft and communicate with a duct or channel 95 formed in the bottom 16 of the casing *a* and leading to the outside of the latter.

If water starts to enter the casing along the rock-shaft, it runs into the outermost annular groove 94 and is conducted outside of the casing through the duct or channel 95.

If the quantity of water is more than the outermost groove 94 can take care of, the second and third grooves will take care of it.

It is preferred to provide the cover with the inverted T-shaped slot by means of the ribs 72, whereby the amount of metal in the cover may be reduced, but it is not desired to limit the invention in this respect.

One embodiment of the invention is herein shown, but it is not desired to limit the invention to the particular construction shown.

What I claim is:

1. In a circuit controlling apparatus, in combination, a casing, an oil well attached thereto, a switch in said oil well having a movable member, a support for said movable member extended into said casing, a rock-shaft extended into and outside of said casing, a toggle connecting said rock-shaft with the support for said movable member, a crank fast on said rock-shaft outside of said casing, a handle loose on said rock-shaft to be vertically suspended therefrom outside of said casing and provided with a device for engaging one surface of said crank outside of said casing to positively rotate said rock-shaft substantially a half turn in one direction to move the movable switch member into its closed position, and to engage the opposite surface of said crank and initially positively move said rock-shaft in the opposite direction, and means rendered effective by the movement of the movable switch member into its closed position to supplement the initial opening movement of the movable member by said handle and rock-shaft and complete the opening movement of said movable member independently of the rock-shaft and handle.

2. In a circuit controlling apparatus, in

combination, a casing, an oil well detachably secured thereto, a switch in said oil well, a switch-operating mechanism located in said casing and operatively connected with the switch in said well, said mechanism including a rockshaft having one end extended outside of said casing and having fast thereon a crank visible from outside the casing to indicate the condition of said switch, and a handle loose on said rockshaft to be vertically suspended therefrom outside of said casing and provided with a device for engaging said crank to move the latter in opposite directions.

3. In a circuit controlling apparatus, in combination, a casing, a switch-operating mechanism located in said casing, a switch operated by said mechanism, and a handle located outside of said casing and normally disconnected from said mechanism and vertically suspended and free to be moved through an arc of material length without actuating said switch-operating mechanism to open the switch and to be returned to its normal vertical position with the switch in its closed or open position, and means outside of said casing for operatively connecting said handle with said operating mechanism and for indicating the condition of said switch.

4. In a circuit controlling apparatus, in combination, a stationary switch member, a movable switch member located below said stationary switch member, a reciprocating support for the movable switch member extended above the stationary switch member and provided with a cross head, a rockshaft located below said cross head, a toggle connecting said rockshaft with the under side of said cross head to close the movable switch member by rotation of said rockshaft, a spring carried by and bodily movable with said cross head and compressed by the closing movement of said movable switch member to render it effective to move the said switch member independently of said rockshaft.

5. In a circuit controlling apparatus, in combination, a movable switch member, a support therefor including a crosshead provided with a socket, a spring located in said socket, a plunger extended into said socket and acted upon by said spring, a rod attached to said plunger and extended outside of said socket, and means on said rod for limiting the movement of said plunger by said spring.

6. In a circuit controlling apparatus, in combination, a stationary switch member, a movable switch member located below the stationary switch member, a support for said movable member comprising a cross head and substantially parallel insulating bars connecting said crosshead with said movable member and extended above said stationary switch member, a rockshaft located below said

crosshead between said bars, and a toggle connecting said rockshaft with said crosshead.

7. In a circuit controlling apparatus, in combination a stationary switch member, a movable switch member located below the stationary switch member, a reciprocating support for said movable switch member extended above said stationary switch member and provided with a cross head above said latter switch member, a rock-shaft located between said stationary switch member and said cross head, and a toggle located between said rock-shaft and said cross head and having one member of said toggle connected with the under side of the said cross head.

8. In a circuit controlling apparatus, in combination, a casing provided with an opening in its bottom, a slab of insulating material located below said opening in line therewith and itself provided with an opening, means extended through the opening in the bottom of said casing for supporting said slab from said casing, circuit terminals secured to said slab, a movable switch member located below said slab and co-operating with said circuit terminals, a support for said movable switch member extended through the opening in said slab into said casing, and means within said casing for moving said support and its attached switch member.

9. In a circuit controlling apparatus, in combination, a casing provided with an opening in its bottom, a slab of insulating material located below said opening in line therewith and itself provided with an opening, means extended through the opening in the bottom of said casing for supporting said slab from said casing, circuit terminals secured to said slab, a movable switch member located below said slab and co-operating with said circuit terminals, a support for said movable switch member extended through the opening in said slab into said casing, guides for said support erected upon said slab, a rock-shaft, a toggle connecting said rock-shaft with said support, a handle loosely mounted on said rock-shaft outside of said casing and provided with a lug, and an arm fast on said rock-shaft with which said lug co-operates.

10. In a circuit controlling apparatus, in combination, a casing provided with a bottom having an opening between its ends, an insulating member horizontally arranged below said bottom and provided with an opening registering with the opening in the bottom of said casing, means extended through the opening in the bottom of the casing for suspending the said insulating member, stationary contact members spaced apart and secured to said insulating member on opposite sides of the opening therein, a movable contact member located below said insulating member and bodily movable toward and from the same and having its ends co-operating

with said stationary contact members, an insulating barrier secured to said movable contact member and extended up into the casing through the opening in the insulating member and through the opening in the bottom of the casing, and mechanism within said casing above said horizontally arranged insulating member for moving said movable contact member.

In testimony whereof, I have signed my name to this specification.

JOHAN M. ANDERSEN.
